(57) **CLAIM**

The ornamental design for a hand-held electronic football game, as shown.

DESCRIPTION

FIG. 1 is a perspective view of a hand-held electronic football game showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan thereof; and,

FIG. 8 is a bottom plan view thereof; similar to FIG. 7 with wrist strap removed.

The broken line showing of the wrist strap is for illustrative purposes only and forms no part of the claimed design.
